United States Patent Office

Des. 192,654
Patented Apr. 24, 1962

192,654

BOTTLE

Roy W. Dike, Northbrook, Ill., assignor to Continental
Can Company, Inc., New York, N.Y., a corporation of New York

Filed Sept. 6, 1961, Ser. No. 66,620

Term of patent 14 years

(Cl. D58—5)

Fig. 1

FIGURE 1 is a front top perspective view of a bottle showing my design,

The dominant features of my design reside in the portions shown in full lines.

I claim:

The ornamental design for a bottle, as shown and described.
